UNITED STATES PATENT OFFICE.

CHARLES J. LINDHOLM, OF MILWAUKEE, WISCONSIN.

ANIMAL-RELEASING DEVICE.

1,171,448.

Specification of Letters Patent. Patented Feb. 15, 1916.

Application filed February 19, 1915. Serial No. 9,326.

To all whom it may concern:

Be it known that I, CHARLES J. LINDHOLM, a citizen of Sweden, residing at Milwaukee, in the county of Milwaukee and State of Wisconsin, have invented certain new and useful Improvements in Animal-Releasing Devices, of which the following is a specification.

This invention relates to improvements in animal releasing devices and its object is to provide a device whereby a number of animals confined in a series of stalls may be simultaneously released in time of necessity, as in case of fire and the like.

With the foregoing and other objects in view the invention consists in the combination and arrangement of parts to be herein-after fully described in the following specification, pointed out in the claims and illustrated in the accompanying drawings which form a part of said specification and in which—

Figure 1 is a front view of my improved device as applied to a series of stalls in a stable. Fig. 2 is a plan view of the same. Fig. 3 is a vertical section taken on the line 5—5 of Fig. 1; and Fig. 4 is a detailed front elevation of the invention showing the retaining device in released position.

Like reference characters indicate corresponding parts throughout the several views.

The reference numeral 1 designates the outside wall of a stable or like building which in its interior is divided into a plurality of stalls by partitions 2 in each of which the ordinary feed trough 3 is arranged. To the several feed troughs I secure a rotary shaft 4 by means of the several brackets 5, said shaft 4 being formed with a plurality of notches 5^a and upon each notched portion of the shaft a bracket 6 is secured, said bracket 6 being apertured as at 7 and through said aperture a pin 8 is normally projected which terminally engages the notched portion of the shaft 4. The pin 8 is carried by a flat spring 9 which is secured by bolt 10 to the bracket. The bracket 6, further, is formed in its free end with an opening 11 through which a curved bolt 12 normally projects that extends into a housing 13 secured to the under side of the feed trough. About said curved bolt a spring 14 is disposed that tends to rotate said bolt. The bolt carries the ordinary hitching ring 15. Referring again to the

rotary shaft 4, one end of the same extends through one end of the stable and is bent at an angle with the balance of the shaft and carries a weight 16 which is normally retained in set position, shown in full lines in Fig. 4, by the spring lever 17.

To release one animal from the stall the operator raises the pin 8 out of engagement with shaft 4 and then manually raises the bracket 6 out of engagement with the curved bolt 12 when the ring 15 will be removed from the bolt by rotation of the same. To release all of the animals simultaneously the operator raises the lever 17 out of engagement with the curved end of the shaft 4 when the weight 16 will gravitate into the position shown in dotted lines in Fig. 4 and so move the shaft and all of the brackets 6 out of engagement with the curved bolts 12 permitting animals in the stalls to escape and take the rings 15 with them.

What is claimed is:

1. A releasing device of the type described, including a longitudinal member, means for supporting the same, a bracket movably applied to said longitudinal member, a spring resting upon said bracket and having one end secured to said bracket and provided at its opposite end with a detent-like pin arranged to extend through said bracket and engage said longitudinal member, a halter or strap attaching member, and a resiliently exerted bolt controlled by said spring-pin retained bracket, said halter or strap-attaching member being connected to said bolt.

2. A releasing device of the type described, including a longitudinal member having a notch, means for supporting said longitudinal member, a bracket movable upon, and having said longitudinal member extending therethrough, a spring having one end secured to said bracket, the opposite end of said spring being equipped with a detent-like pin extending through said bracket and engaging a notch in said longitudinal member, a bolt equipped with a halter or strap-attaching member, said bracket having an opening receiving one end of said bolt, and a resilient member applied to exert pressure upon said bolt and provide for the removal of said strap-attaching member from the latter as said bolt is disengaged from said bracket.

3. A releasing device of the type de-

scribed, including a rotary longitudinal rod member, means for supporting the same, a bracket applied to turn with said rotary longitudinal rod member, means for the retention of said rotary longitudinal rod member in set position, a bolt held in engagement with said bracket and equipped with a strap or halter-attaching member, and a spring applied to exert pressure upon, and cause said bolt to become disengaged from said bracket as the latter receives movement

from the turning or actuating of said rotary longitudinal member.

In testimony that I claim the foregoing as my own I have hereto affixed my signature in the presence of two subscribing witnesses. 15

CHARLES J. LINDHOLM.
